UNITED STATES PATENT OFFICE

EDWIN F. GUTH, OF WEBSTER GROVES, MISSOURI

DESIGN FOR A LIGHTING UNIT FOR REFLECTED ILLUMINATION

Application filed February 24, 1931. Serial No. 38,794. Term of patent 14 years.

To all whom it may concern:

Be it known that I, EDWIN F. GUTH, a citizen of the United States, residing at Webster Groves, in the county of St. Louis and State of Missouri, have invented a new, original, and ornamental Design for a Lighting Unit for Reflected Illumination, of which the following is a specification, reference being had to the accompanying drawings, forming part thereof, in which—

Fig. 1 is a front elevation showing my new design; and

Fig. 2 is a cross section.

I claim:

The ornamental design for a lighting unit for reflected illumination, as shown.

EDWIN F. GUTH.
